WIRED BRASSIÈRE

Gerald W. Gluckin, New York, N. Y.

Application July 16, 1947, Serial No. 761,189

1 Claim. (Cl. 2—42)

1

This invention relates to wired brassières. More particularly, the invention pertains to that type of wired brassière wherein a single wire element is used which is common to both bust cups and which only reinforces the inner edge of each cup. Said element typically includes two circumferentially spaced vertically extending reaches; one associated with each bust cup.

It is an object of the invention to provide a brassière of the character described in which the wire element is secured neither to the bust cups nor to any other part of the brassière but rather is slidably insertable in retaining pockets alongside the inner edges of the bust cups so that said element can be inserted and removed by the user with ease.

It is another object of the invention to provide a brassière of the character described in which the wire element has a very simple shape so that it can be manufactured at a low cost and be incorporated in the brassière at the factory by relatively unskilled help.

It is a further object of the invention to provide a brassière of the character described in which a simple yet effective means is employed to prevent the wire element from falling out, this means being so constructed as not to unduly complicate the withdrawal of said element and to be easily moved aside at such time as the element is to be slid out of its retaining pockets.

Other objects of the invention will in part be obvious and in part be pointed out hereinafter.

The invention accordingly consists in the features of construction, combinations of elements and arrangements of parts which will be exemplified in the construction hereinafter described and the scope of which will be indicated in the appended claim.

In the drawings, in which is shown one of the various possible embodiments of this invention,

Fig. 1 is a perspective view of a brassière embodying the invention, the same being shown on a lay figure for purpose of illustration;

Fig. 2 is an inside view of the brassière as it appears when flat;

Fig. 3 is an enlarged inside fragmentary view of the central portion of the brassière;

Figs. 4 and 5 are sectional views taken substantially along the lines 4—4 and 5—5 respectively of Fig. 3; and

Fig. 6 is a perspective view of the wire element.

Referring now to the drawings, 10 denotes a brassière constructed in accordance with the in-

vention. Said brassière comprises two like bust cups 12, 14 whose bust-receiving portions are of conventional construction comprising by way of example an upper fabric panel 16 and a lower fabric panel 18 joined to each other by stitching along an arcuate line 20, which is downwardly concave and which passes across the center of the cup. The inner side of the lower panel 18 is reinforced by a pair of crossed angularly disposed wide fabric strips 22, 24 attached to said panel by a plurality of rows of stitching 26, 28 running parallel to the longitudinal edges of said strips. In addition, a piece of netting 30 co-extensive with the panel 18 may be provided to overlie said panel and the strips 22, 24. The inner edges 32 of both bust cups are substantially straight and vertical, said inner edges being held in spaced relationship by the use of a construction hereinafter described in detail. The outer edges of the bust cups have secured thereto conventional fabric panels 34 which extend under the arm and around to the back of the wearer. Standard shoulder straps 36 connect the tops of the bust cups to the panels 34 at the rear of the brassière.

In order to lessen circumferential strain upon a central wire element hereinafter described, fabric means is provided to join said bust cups, said means being so disposed that it does not interfere with the deep and wide separation between the inner edges 32 of the bust cups. Said means comprises a narrow, doubled two-ply strip 38 of fabric located between the two bust cups and disposed at the bottoms of the inner edges thereof. Said piece of fabric is secured to the bust cups by circumferentially extending stitching 40 and two rows of vertically extending stitching 42.

It will be noted that the front portion of the doubled strip 38 is disposed on the exterior surfaces of the bust cups and the rear portion of said strip overlies the interior portions of the bust cups along the bottom marginal portions thereof, and that the lower edges of the bust cups are quite close to the folded edge of the strip. Thus the portions of the strip which do not bridge the space between the two bust cups constitute, in effect, portions of the bust cups and, more specifically, comprise bindings for the lower marginal portions thereof. Inasmuch as said strip is a part of each bust cup, it may be continued along the bottom edge of each cup in order to lend a pleasing appearance to the brassière. Furthermore, it is convenient to allow the strip to extend along the bottom edges of the panels 34, as well, for the same reason.

Said strip extends beyond the tips of the panels 34 and the extending portions carry a hook 44 and a series of eyes 46, respectively, for the purpose of detachably securing the two ends of the brassière together at the back of the wearer. Desirably, a circumferentially elastic insert 48 may be included, as is customary in the art.

The vertical inner edges 32 of the bust cups are held in erect position on a wearer by means of a reinforcing element 50 composed of a self-form-maintaining material which, preferably, is somewhat resilient. A suitable material for this purpose is steel in the form of wire, which may be enameled if the steel is not stainless in order to prevent the same from rusting. The element 50 includes a circumferentially disposed base 52 from the two ends of which upward parallel reaches 54, 56 extend vertically.

Each inner edge 32 of the bust cups is provided with a pocket to receive freely a vertical reach of the wire element. Such pockets are indicated by the numerals 58 and are best illustrated in Fig. 5 where they will be seen to be formed by fabric tapes 60 superimposed on the side marginal portions of the bust cups at the backs thereof, the tapes being stitched to the bust cups only along the longitudinal edges of the tapes, thus leaving free and clear the longitudinally extending central portions of the tapes. Said pockets are open at their bottom ends 62 whereby to permit simple insertion of the wire element therein.

It will be observed that both pockets terminate within the area enclosed by the doubled strip 38 between the vertical rows of stitching 42, this particular portion of the strip having its upper edges unconnected to one another. In this fashion, the central portion of the strip, which serves to hold the two bust cups together, also functions to prevent the wire element 50 from falling out of the pockets.

When it is desired to remove the wire element, it simply is necessary to distort the doubled-over portion of the strip 38 sufficiently to expose the base 52 of the wire element, whereupon the same readily can be withdrawn.

It thus will be seen that there is provided a brassière which achieves the several objects of the invention and is adapted to be employed successfully on a commercial scale.

As various possible embodiments might be made of the above invention, and as various changes might be made in the embodiment above described, it is to be understood that all matters herein set forth, or shown in the accompanying drawings, is to be interpreted as illustrative and not in a limiting sense.

Having thus described the invention, there is claimed as new and desired to be secured by Letters Patent:

A brassière comprising a pair of spaced bust cups, each of said bust cups having a substantially straight vertical inner edge portion and a base, the vertical inner edge portion of each bust cup meeting the base of said bust cup to form an inside bottom corner, the inner edge portion of each bust cup extending upwardly from adjacent the base of said bust cup, said portions being spaced from one another circumferentially of the brassière, each of said edge portions having a vertically extending pocket, each pocket having a bottom end, said bottom ends being open and unconnected with one another, a U-shaped wire element comprising a base having ends and a pair of spaced upwardly extending reaches at said ends of the base of the wire element, said reaches being slidably disposed in said pockets, and means to hold the inside bottom corners of said bust cups together independently of said wire element, said last-named means comprising a strip of non-elastic fabric which is doubled over along its longitudinal central axis thus forming a doubled over portion and a folded edge, said strip of fabric constituting a body-encircling band which runs along and is secured to the bases of the bust cups and extends across the space between the two bust cups, the folded edge of said strip being lowermost, a part of the doubled over portion of the strip being disposed between the bust cups, said part of the doubled over portion being unconnected except at the folded edge and forming a receptacle within which the base of the wire element is disposed thereby to prevent the reaches of said element from accidentally sliding out of the vertical pockets, the bottom ends of the vertical pockets terminating within said part of the doubled over strip extending between the bust cups.

GERALD W. GLUCKIN.
